CATHODE STRUCTURE

Ilia Emmanuel Mouromtseff, Montclair, and George M. Dinnick, Bloomfield, N. J., assignors to Westinghouse Electric & Manufacturing Company, East Pittsburgh, Pa., a corporation of Pennsylvania

Application June 24, 1941, Serial No. 399,454

5 Claims. (Cl. 250—27.5)

This application is a continuation-in-part of our copending application Serial No. 360,367, filed October 9, 1940, for "Ultra-high frequency oscillator."

The invention relates to cathodes and particularly to directly heated cathodes.

An object of our invention is to provide a cathode having no magnetic field or a very weak one at its active surface.

Another object of our invention is to provide a cathode which will produce a plane wave of electrons.

Another object of the invention is to provide a cathode which is capable of withstanding potential differences of the order of thousands of volts between its own potential and the potentials of other electrodes.

Another object of our invention is to provide a cathode of sturdy construction in which the active electron-emitting portion is confined to a desired plane of the cathode.

Other objects and advantages of the invention will be apparent from the following description and drawing in which:

Fig. 1 is a view in cross section through a portion of a discharge device to which our invention has been applied.

Fig. 2 is a perspective view of the cathode of Fig. 1.

Fig. 3 is a cross sectional view through a modification of the cathode of Fig. 2.

Fig. 4 is a perspective view of a still further modification.

In our copending application Serial No. 360,367, filed October 9, 1940, for "Ultra-high frequency oscillator" we desired plane waves of electrons to be applied to a plurality of openings in a hollow body resonator enclosed in a high vacuum and little or no magnetic field at the surface of the cathode. The potential difference between the various electrodes is of the order of thousands. The present invention is the result of our attempts to find a cathode that would more satisfactorily meet the exacting requirements of a cathode for our oscillator.

While indirectly heated oxide coated cathodes would supply the copious supply of electrons desired, these oxide coated cathodes necessitated a complicated structure including relatively large ceramic insulators which are difficult to out-gas to the required degree of perfection required by our device. We, accordingly, devised the present directly heated cathode for our hollow body resonator device and this cathode is, of course,

applicable to other forms of discharge device having similar requirements.

In Fig. 2 we have illustrated a preferred embodiment of our cathode. This cathode comprises a metal ribbon which may be of nickel, thoriated tungsten, plain tungsten or a nickel-cobalt-titanium alloy sold under the trade-name of "Konal."

This ribbon is preferably of a thickness of 5 to 10 mils. The central portion of this ribbon is formed into a flat plane face 10 which will be the electron-emitting portion of the cathode. Our special means in this modification of making this plane face 10 the electron emitting portion is to provide a plurality of longitudinal slots 11 in this face. These slots may be of any number and size, but from the point of efficiency we prefer to limit the material removed from this active area by those slots to about 10% or less. Presence of said slots, which extend substantially the length of the top plane face 10, divides said face into a plurality of parallel spaced strips 12 all in said plane and all integral with common end folds 13, 14 at opposite ends of said strips.

Because of the reduced cross-sectional area through the face 10 caused by the removal of the material, the intermediate strips 12 between the slots will be heated to a temperature greater than the rest of the ribbon. The higher temperature of the strips 12 will make them electron-emitting while the other portions are below that temperature. The portion of the ribbon adjacent the plane surface 10, is preferably curved over at the two sides and comprises solid metal folds 13 and 14 and the next portions 15 and 16 are bent into a rear face situated in a common plane slightly spaced from and parallel with the front face 10.

The ends 17 and 18 of the ribbon are bent away at right angle from the plane formed by the two portions 15 and 16, which have a space 19 therebetween to prevent any sparking between the two faces 17 and 18. These ends 17 and 18 of the ribbon are attached as by welding to two sturdy standards 19 and 20.

In operation a current, for example, passes up the standard 19 as indicated by the arrow to the face 17 and then passes outward, in the rear plane in conductive rear portion 15, thence through the curved face or fold 13, and then across the more resistive face 10 to the left to the other curved face or fold 14. During this passage across the face 10, the current heats up this active face to a temperature above that of

the rest of the ribbon, because of the reduced cross section.

A copious supply of electrons is emitted in plane waves from the surface of this face 10. The current then passes around the curved face 14 and thence in a direction to the right through the conductive rear face 16, parallel with the front face 10, and then through the end 18 of the ribbon and out through the standard 20, as indicated by the arrow associated therewith.

It will be noted that the direction of the current, as indicated by the arrows, in the front face 10 is opposite to the direction of the current in the rear faces 15 and 16 parallel to and slightly spaced from this front face 10.

The magnetic field from the current in the front face 10 will be substantially neutralized by the magnetic field from the oppositely flowing current in the rear faces 15 and 16, and it will have little or no effect on the electron flow caused by the magnetic field of the heating current.

The cathode is self-supporting and the opposite magnetic fields of the front and rear faces will aid in eliminating from the cathode, a tendency to collapse when heated to the high temperature required for certain installations.

Such an installation is disclosed in Fig. 1 where the cathode has its active face 10 closely spaced in parallel arrangement from a control grid 25. This control grid in this disclosure is supported in parallel arrangement with the cathode face by a plurality of conductive rods 26, symmetrical with the two cathode standards 19 and 20, and these rods are sealed through a cup-shaped casing of insulation 27. The rim of this insulation 27 is sealed to a copper member 28 silver soldered to a disk 29 in turn silver soldered to a hollow body resonator 30 having openings 31 in a plane parallel to the grid face 25 and the cathode face 10.

A supporting disk 32 and an adjusting screw 33, attached thereto, and screw threaded to the disk 29, permits the spacing adjustment of the opening 31 in the hollow body resonator to be spaced as desired from the cathode and grid. Inside of the hollow body resonator 30, is a receiving face 34 for the electrons, and this face may constitute a portion of a water-cooled electrode 35, which is either separate from or connected to the hollow body resonator 30 as desired.

In place of the slots 11 in Fig. 2, we may utilize a ribbon of approximately 10 mils thickness, and then thin the active surface 10' to a thickness of 5 mils by removing material from the back or front or both faces of the central portion of the ribbon, as illustrated in Fig. 3. The other portions 13', 14', 15' and 16' of the cathode ribbon have the thickness of corresponding portions in the modifications in Fig. 2. This reduced thick-

ness will cause this face 10' to have a higher temperature.

In Fig. 4 we have illustrated a modification in which the slotted front face 10 is the same as in Fig. 2, but the continuation of the ribbon from this front face is curved at 40 into a rear face 41 parallel to and spaced from the front face. The end tabs 42 and 43 are bent downward on the one side and welded to the conductor or standards 19, 20. The magnetic field of the current in the front face 10 is more completely neutralized by the magnetic field of the current in the rear face 41 than in Fig. 2. The rear cathode structure of Fig. 3 may be modified in a manner similar to that of Fig. 4.

It is apparent that other modifications may be made in the preferred embodiments illustrated and, accordingly, we desire only such limitations to be imposed upon our invention as is necessitated by the spirit and scope of the following claims:

We claim:

1. A cathode comprising a metal ribbon folded into a plurality of planes and means increasing the electrical resistance of the metal extending between folds thereof in one of said planes to exceed the resistance of the metal comprising said folds.

2. A cathode comprising a metal ribbon folded into a plurality of planes, the portion of the ribbon in one of said planes having slots therein substantially from one fold to another fold and the ribbon at the folds thereof being more conductive than at said slotted portion.

3. A cathode comprising a metal ribbon having an active plane slotted face and having continuations of the ribbon from said slotted face which offer less resistance to current flow than said slotted face, said continuations having portions extending behind and rearward with respect to said slotted face for mounting and current conducting purposes.

4. A cathode comprising a metal ribbon having an active plane slotted face and a rear face parallel to said active plane slotted face, said front and rear faces having different resistance characteristics.

5. A cathode comprising a metal ribbon having an active plane slotted face and a rear face parallel to said active plane slotted face and formed as a continuation thereof and having greater conductivity lengthwise than the lengthwise conductivity of the slotted face, whereby the current in said front face will flow with greater heating effect and will be in a direction opposite to the current in the rear face.

ILLIA EMMANUEL MOUROMTSEFF.
